AERIAL PROPELLER

Richard W. Kloepfer, Teaneck, N. J.

Application May 21, 1940, Serial No. 336,321

2 Claims. (Cl. 170—165)

This invention relates to aerial propellers and has particular reference to an improved four bladed propeller which is so constructed and arranged as to provide greater efficiency and economy of operation.

As the aerial propeller produces a turbulence in the air in the wake of each blade, it has been found desirable to so position the blades on the hub that the forward travel of the propeller will be such as to place the leading edges of the blades forwardly of the disturbance or wake produced by the blades. This has led to the development of the two-bladed propeller with the blades diametrically disposed on the hub as most practical and efficient, since the blades being so disposed apart, the disturbance in the wake of each blade will pass to the rear of the succeeding blade due to the translatory or forward movement of the propeller. It has also been found that in three and four bladed propellers in which the propellers project radially from the hub in a common plane at angles of 120° and 90° apart respectively that the forward motion of the craft is not sufficient to carry the blades of the propeller out of the wake of the preceding blades respectively and in an undisturbed air medium. It is, therefore, an object of the present invention to provide a four bladed propeller having the desirable characteristics of the two bladed propeller and which overcomes the objections to the usual types of three and four bladed propellers.

The invention, therefore, provides a four bladed propeller consisting of two pairs of blades mounted on a common shaft to turn together and which pairs of blades project outwardly in opposite directions, the blades of each pair being pitched in the same direction and staggered with reference to each other to dispose one of the blades of each pair rearwardly of the other blade and in advance thereof in the direction of rotation of the blades.

The invention further comprehends a four bladed propeller of the indicated character in which the blades are mounted on the hub tangentially of the shaft with the leading edges of the blades disposed in parallel relation and with the blades rotating in axially spaced orbits, one of the blades of each pair rotating in one of the said orbits and the other blade of each pair rotating in the other orbit.

With the foregoing and other objects in view, reference is now made to the following specification and the accompanying drawing in which there is illustrated the preferred form thereof.

In the drawing:

Fig. 1 is a view in side elevation of a propeller constructed in accordance with the invention.

Fig. 2 is a front view thereof.

5 Fig. 3 is a top plan view.

Fig. 4 is a perspective view of the propeller hub with the blades partially broken away and with one of the blades removed and shown in juxtaposition.

10 Referring to the drawing by characters of reference, the propeller includes a hub designated generally by the reference character 10, which is adapted to be affixed to the propeller shaft 11 for rotation therewith in a counterclockwise direction as shown by the arrow in Fig. 2.

The hub 10 is preferably provided with a plurality of bosses 12 having bores 13 extending longitudinally therethrough and opening above and below the hub, four bosses being shown, two 20 of which are located on one side of the hub and two on the opposite side thereof and axially spaced fore and aft with the forward bosses in lateral alignment and the rear bosses in lateral alignment and the bores parallel and substantially tangential to the shaft.

The propeller further includes a plurality of pairs of blades 14 and 15 and 16 and 17, the blades 14 and 15 constituting one pair and projecting outwardly from the hub in one direction, 30 while the blades 16 and 17 constitute the other pair and project outwardly from the hub in the opposite direction. Each blade is provided at its inner end with a shank 18 adapted to be received in the bore 13 of a boss 12, the blades 14 and 15 of the one pair being staggered with reference to each other to rotate in axially spaced orbits, the shank of the blade 14 being mounted in the forward bore on one side of the hub, while the shank of the blade 15 is mounted 40 in the rear bore on the opposite side to thus dispose the blade 15 rearwardly of the blade 14 and in advance of the blade 14 in the direction of rotation of the propeller. Similarly the blades 16 and 17 are staggered with reference to each

45 other and in opposite relation to the staggering of the blades 14 and 15 to rotate in axially spaced orbits, the shank of the blade 16 being mounted in the bore on one side of the hub and the shank of the blade 17 being mounted in the bore on the opposite side of the hub to thus dispose the blade 17 rearwardly of the blade 16 and in advance of the blade 16 in the direction of rotation of the propeller. The propellers 50 are pitched in the direction of rotation and the driving faces 19 and 20 of the blades 14 and 15

are disposed in parallel planes, while the driving faces 21 and 22 of the blades 16 and 17 are disposed in parallel planes and with the leading edges, as illustrated, disposed in parallel relation.

In order to provide means for securing the blades to the hub bosses for turning movement on their longitudinal axes to adjust the pitch thereof, each blade is provided at its juncture with the shank 18 with a serrated shoulder 23 adapted to mesh or engage with the correspondingly serrated terminal 24 of the boss and the free threaded end 25 of the shank is adapted to receive thereover a washer 26 having a serrated face 27 to mesh with the serrated opposite end 28 of the boss. A nut 29 engages over the threaded terminal of the shank to secure the blade in assembled relation with the hub and to rotate the blade at the desired pitch.

In operation, the propeller, rotating in a counter-clockwise direction as indicated by the arrow in Fig. 2, will exert a forward thrust by the blades 14 and 15 acting as a double screw and the blades 16 and 17 acting as another double screw. The blade 15 being in advance of the blade 14 in the direction of rotation and axially rearward thereof, the slip stream produced by the blade 14 will not affect the density of the air in the region of the blade 15 and similarly, the blade 17 being in advance of the blade 16 and axially rearward thereof, the slip stream produced by the blade 16 will not affect the density of the air in the region of the blade 17. Furthermore, the forward travel of the propeller will be such that the following blades, such as the blades 16 and 17 will operate in the air medium forwardly of the wake of the blades 14 and 15 respectively, and the slip streams of the forward blades 14 and 16 will push rearwardly the turbulence in the wake of the blades 15 and 17 respectively so that the blade 15 will operate in the compact slip stream of the blade 16 and the blade 17 will operate in the compact slip stream of the blade 14 whereby the rear blades 15 and 17 will increase the volume and backward velocity of the slip streams produced by the forward blades 14 and 16.

As illustrated, the blades are preferably stream-lined in cross sectional configuration, the leading edges thereof being convex and merging into convex front faces which converge with reference to the plane driving faces into longitudinally curved trailing edges. While the propeller is illustrated with the blades mounted for counter-clockwise rotation, it is obvious that the mounting thereof may be reversed for clockwise rotation.

What I claim is:

1. In an aerial propeller, a hub, a pair of pro-

peller blades having their inner ends connected to said hub on opposite sides of the axis thereof in diagonally spaced apart relation and projecting outwardly from the hub in the same direction, and a second pair of propeller blades having their inner ends connected to said hub on opposite sides of the axis thereof in spaced apart relation on a diagonal reversed with reference to the diagonal relation of the first pair of blades and corresponding to the diagonal angularity thereof and the spacing of the blades of the first pair and projecting outwardly from the hub in the same direction and opposite to the direction of said first pair of blades, and the blades of both pairs being pitched in the same direction and arranged with reference to each other to dispose one blade of each pair axially rearward of the other and in advance thereof in the direction of rotation and with one blade of each pair rotating in one orbit and the other blade of each pair rotating in an axially spaced orbit, and means for securing the blades individually in selectively adjusted positions as to pitch.

2. In an aerial propeller, a hub having four parallel blade receiving sockets arranged with two sockets on one side of the axis of the hub spaced respectively forward and rearward axially and two sockets on the opposite side of the axis of the hub respectively spaced forward and rearward axially, a pair of propellers having their inner ends respectively affixed in two of said sockets to dispose said blades on opposite sides of the axis of the hub in diagonally spaced apart relation projecting outwardly from the hub in the same direction, and a second pair of propeller blades having their inner ends affixed in the remaining sockets to dispose said blades on opposite sides of the axis of the hub in spaced apart relation on a diagonal reversed with reference to the diagonal relation of the first pair of blades and corresponding to the diagonal angularity thereof and the spacing of the blades of the first pair and projecting outwardly from the hub in the same direction and opposite to the direction of said first pair of blades and the blades of both pairs being pitched in the same direction and arranged with reference to each other to dispose one blade of each pair axially rearward of the other blade of said pair and with the axial rearward blade in advance of the other blade in the direction of rotation and with one blade of each pair rotating in one orbit and the other blade of each pair rotating in an axially spaced orbit, and means for holding the blades in the socket and for securing the same individually in selectively adjusted positions as to pitch.

RICHARD W. KLOEPFER.
